UNITED STATES PATENT OFFICE.

JOHN WILLIAM CALDWELL, OF TORONTO, ONTARIO, CANADA.

EXPANSION-BIT.

1,066,707.

Specification of Letters Patent.

Patented July 8, 1913.

Application filed June 24, 1908, Serial No. 440,178. Renewed December 2, 1912. Serial No. 734,628.

To all whom it may concern:

Be it known that I, JOHN WILLIAM CALDWELL, a subject of the King of Great Britain, and resident of the city of Toronto, in the 5 county of York, in the Province of Ontario, in the Dominion of Canada, have invented certain new and useful Improvements in Expansion-Bits, of which the following is a specification.

- 10 The invention relates to improvements in expansion bits as described in the following specification and illustrated in the accompanying drawings that form part of the same.
- 15 The invention consists essentially in the novel construction and arrangement of parts whereby an adjustable cutter is arranged in the spiral body portion of a bit formed in cross section with parallel straight faces of 20 greater width than half the diameter of the bit, so as to form, in its various positions, a continuation of the said spiral at one side of the central lead screw.

The objects of the invention are to devise 25 an expansion bit which will cut various sizes of holes evenly and true and carry the chips clear of the hole without choking, and to provide a bit of simple and durable construction which may be sharpened readily 30 and easily and quickly adjusted.

The present invention relates particularly to the adaptation of the auger bit described in my co-pending application 440,177 to an expansion bit.

35 In the drawings Figure 1 is a perspective view of the bit broken intermediate of its length, and showing a cross section. Fig. 2 is a detail of the cutting end. Fig. 3 is a detail of the cutting end showing the movable cutter extended. Fig. 4 is an end view of the bit.

Referring to the drawings 1 is the spiral having the body 2 formed with parallel straight faces 3 connecting the side flanges 4 45 laterally projecting at the outer edges, thus forming a pair of spiral channels of considerably greater width than half the diameter of the bit. The body 2 is thickened at the lower end 5 and sharpened on one side to a cutting edge 6 extending from the center to the outer edge, and on the other side provided with a dove-tail shaped channel 7 extending from side to side thereof in a perfectly straight line.

8 is a straight shallow channel formed 55 above the dove-tail channel 7 having an inwardly beveled upper side 9.

10 is an adjustable cutter having a dove-tail portion 11 extending into the dove-tail channel 7 and sliding therein and a downwardly and outwardly flaring cutting portion 12 extending therefrom and sloping upwardly and inwardly, forming a continuation of the upper surface of the spiral body 2. The upper edge 13 of the cutter 10 is roughened with file marks, or in any other suitable manner.

14 is a block having a beveled upper edge and fitting into the channel 8 and rigidly secured in place by a pair of screws 15. The 70 under surface of the block 14 is roughened in a corresponding manner to the upper side of the cutter, and is held tightly against said cutter to hold it in an adjusted position by the pressure of the screws 15.

Hitherto it has been impossible to adapt a spiral form of bit to expansion bits on account of the lack of clearance in the spiral portion, which would choke and prevent the proper clearing of the cutter, but in the present invention this difficulty is entirely overcome by the peculiar formation of the spiral portion which is so formed that the channels in which the chips have to travel are much wider than the width of the chips cut, and the 85 wide channels extend directly from the cutting edges, so that the chips can not choke or wedge between the flange of the bit and the side wall of the hole being cut.

16 is a lead screw extending downwardly 90 from the center of the body 2 having a double thread 17 formed with an undercut inner surface and terminating in a pair of chisel points 18. One of the threads 17 forms a continuation of the cutting edge 16 so that 95 the lead screw on being inserted in the wood draws the bit inwardly and the said cutting edge to its work.

The chip cut by the stationary cutter travels up the spiral without choking or binding, 100 and there is sufficient room in the other channel for the outer chip cut by the expansion cutter to travel freely.

19 and 20 are dove-tail vertical slots formed in the outer side of the adjustable 105 cutter 10 and in the side of the bit adjacent to the stationary cutter 6 respectively having the side walls thereof tapered slightly from

the bottom, said slots being also arranged centrally in relation to the flattened faces 19^a and 20^a in the cutters 6 and 10 respectively.

21 and 22 are side cutters having tapered 5 dove-tail portions adapted to fit into the dove-tail slots 19 and 20 and to wedge tightly therein with the sharpened cutting portion 23 projecting below the lower end of the bit.

The cutters 20 and 21 are wedged tightly 10 into place, and when worn out may be easily removed and replaced by new cutters, thus the wearing of the side cutters will not shorten the life of the bit as is the case with various bits at present in use.

15 An expansion bit constructed as herein shown and described is very efficient in its operation, cutting the wood away for the complete diameter of the hole and completely through.

20 The expansion cutter is arranged in the same plane as the stationary cutter. It will thus be seen that the whole area of the surface being cut is cut on the same level, and therefore there will be no danger of any one 25 portion of the bit breaking through the wood on nearing the completion of the hole in advance of the other portion, as is the case with bits at present in use. This feature allows the lead screw to retain its hold in the wood 30 until the outside cutter completes its work, and thus feeds the said cutter inwardly until the hole is completed.

One length of expansion cutter is shown, but it must be understood that longer cutters 35 may be substituted, and very large holes cut by the one size bit.

The bit shown in the drawings shows a shank to be fitted to the ordinary hand brace, but it must be understood that this form of 40 bit may be used in wood working machines, and may also be adapted for use as an auger in boring large holes, and it is only necessary to form the article with the most desirable form of shank for the purpose for which it 45 is to be used.

What I claim as my invention is:—

1. In an expansion bit, a spiral body portion having a cross sectional shape showing parallel straight faces, said straight faces

presenting channels of greater width than 50 half the diameter of the bit, and an adjustable cutter secured in the lower end of said spiral and forming a continuation thereof.

2. In an expansion bit, a spiral body portion having a cross sectional shape showing 55 parallel straight faces, said straight faces presenting channels of greater width than half the diameter of the bit, said body portion having side flanges in cross section appearing as extending laterally from said 60 parallel straight faces at each end and forming guiding shoulders for the chips in their travel along said channels and an adjustable cutter secured in the lower end of said spiral and forming a continuation thereof. 65

3. In an expansion bit, a spiral body portion having a cross sectional shape showing parallel straight faces, said straight faces presenting channels of greater width than 70 half the diameter of the bit, said body portion having a rigid horizontal cutter formed at one side thereof extending from the center outwardly, and an adjustable cutter secured in the opposite side of said body portion to said rigid cutter and forming a continuation of said spiral. 75

4. In a device of the class described, a spiral body portion having flanged edges, said flanges adjacent to the lower end having vertical flattened faces and tapered vertical dove-tailed grooves centrally arranged 80 in relation to said flattened faces, and side spur cutters having tapered dove-tail portions adapted to fit said tapered dove-tailed grooves and flattened inner faces adapted to 85 abut the flattened faces on said body portion and rounded outer sides conforming to the peripheral curve of said body portion and cutting ends projecting beyond said spiral.

Signed at the city of Toronto, in the 90 county of York, in the Province of Ontario, in the Dominion of Canada this 16th day of June, 1908.

JOHN WILLIAM CALDWELL.
